UNITED STATES PATENT OFFICE.

EMIL ANDERSON, OF NEW YORK, N. Y., ASSIGNOR TO THE UNIVERSAL TURBINE COMPANY, OF JERSEY CITY, NEW JERSEY, A CORPORATION OF NEW JERSEY.

TURBINE.

1,097,117.

Specification of Letters Patent.

Patented May 19, 1914.

Application filed August 13, 1912. Serial No. 714,907.

To all whom it may concern:

Be it known that I, EMIL ANDERSON, a citizen of the United States of America, and a resident of New York, county and State of New York, have invented certain new and useful Improvements in Turbine-Engines, of which the following is a specification, reference being had to the accompanying drawings, forming a part thereof.

10 My invention relates to fluid turbine engines and its object is to provide a turbine of simple construction which may be run under different conditions efficiently.

15 I will describe my invention in the following specification and then point out the novel features thereof in appended claims.

20 Referring to the drawings: Figure 1 is a sectional side elevation of an engine embodying my invention. Fig. 2 is a sectional plan view showing the construction and arrangement of some of the parts, this section being taken through one of the controlling valves and its adjacent parts. In Fig. 3 I have shown the apparatus in sectional end elevation. A modified construction is illustrated 25 in Fig. 4 in sectional end elevation on a somewhat enlarged scale.

Like characters of reference designate corresponding parts in all of the figures.

30 10 designates an annular frame upon which the other parts of the apparatus are supported. This is open at 11 so that the exhaust motive fluid may pass out through it and through the base upon which it rests 35 to the air or to a condenser. To this annular frame are affixed side plates 12 and 13 each of which is provided with a stuffing box for the rotor shaft 14 and support the bearings 15 and 16 respectively for this shaft.

40 The rotor comprises a hub 20 which is keyed to the shaft from which projects a ribbed flange 21. Two circumferential rims 22-23 extend to one side of flange 21, and flat rings 24 and 25 parallel with flange 21 are affixed to these rims respectively. These 45 parts form a double annular trough-like structure, of which the open side of the outer trough is toward the axis of the rotor and the open side of the inner trough is away 50 from the axis, so that the two troughs are open toward each other. In each trough is a plurality of rotor rings which divide each trough into a plurality of parallel channels. The rotor rings in the outer trough are des-

ignated by 26 and those in the inner trough 55 by 27. The rotor rings are preferably corrugated so that the channels they form are wave-like. They may be held in place in any desired manner, such for example, as by the construction shown in application 60 for patent Serial No. 714,905, filed by me herewith. The outer trough may be provided with transverse drainage channels discharging through holes 28 in the flange 21. A construction for these drainage channels 65 is also described in the aforesaid application for patent.

The side plate 13 is constructed to form an annular motive fluid chest 17 with which the supply pipe 18 is connected directly. 70 At intervals about this chest are secured stationary nozzle blocks 30 which at intervals fill the space between the open sides of the troughs. These are bored out to receive cylindrical sleeve valves 31 which are 75 arranged to be manually rotated, for example, by the handles 32. Each of these valves is perforated at 33 in that portion of it which crosses the inside of chest 17. It is also provided with a port 34 which may 80 be brought into register with either an advance expansion nozzle 35 or a reverse nozzle 36, or into position to shut off the motive fluid.

37 is a ring rotatably mounted between 85 the fluid chest 17 and the nozzle blocks 30. A pinion 38 which meshes in gear teeth in the side of ring 37 is connected with a handle 39 by means of which the ring may be rotated. Affixed to this ring are 90 blocks 40, one in advance of each of the nozzle blocks, and like the latter these blocks fit the annular space between the open sides of the rotor troughs. The forward end of each nozzle block is beveled 95 as shown, and between it and the adjacent block 40 a fluid passage 41 is formed, which is manually adjustable as to size. The motive fluid is conducted to this device through the chest 17 and valves to 100 the nozzles. Let us assume that the valves are turned to lead the fluid through the advance nozzles 35 into the rotor. These nozzles are so placed that they introduce the motive fluid into the channels in the 105 outer rotor trough from the inside and obliquely. The corrugations of the rotor rings are inclined in the same direction as

the inclination of the nozzles 35 so that the motive fluid is more readily admitted. The fluid thus introduced has a tendency to drive the rotor. On account of its expansion it has a tendency to fill a greater space than that provided in the channels in the outer rotor trough, so some of it will pass through the passages between the nozzle blocks 30 and the movable blocks 40 into the channels in the inner rotor trough, in this case entering from the outside. Here the motive fluid will have a further impelling effect upon the rotor. After the fluid has done its work it passes out of the rotor troughs through the uncovered portions thereof into the inside of the rotor casing, from which it escapes through the opening 11.

On account of the widely varying conditions in practice as to pressures, speeds and loads, I have found it desirable to provide means for varying the proportion of the motive fluid which is used expansively in the inner or secondary rotor trough. This is accomplished by the simple expedient of shifting the blocks 40 in relation to the nozzle blocks 30. It may be seen that these parts may be moved together to entirely close the passage between them, or they may be moved apart to make the passage as large as may be desired. In this way a smaller or greater proportion of the motive fluid is allowed to pass into the inner rotor ring, and this proportion may be varied by a simple mechanical adjustment which may be made while the engine is running, to suit existing conditions. The nozzle blocks are also provided with reverse nozzles 36 and it is obvious that by turning the valves 31 to lead the motive fluid through them into the outer rotor trough, the rotor will be driven in the opposite direction.

In the modification shown in Fig. 4 the motive fluid is first introduced into the inner rotor trough through an expansion nozzle 50 in a stationary block 51. Thence some of it may pass outward into the outer rotor trough through a passage 52 between the fixed block 51 and a movable block 53 similar to blocks 40 heretofore described. More or less of the fluid may be made to pass into the outer rotor trough by varying the size of this passage. Another way of accomplishing this result is to change the position of a deflecting vane 54 which projects from block 51 in advance of the nozzle 50, which may be accomplished by rotating the cam 55. 56 is another valve in the stationary block 51. This is provided with a port by means of which motive fluid may be introduced into the outer rotor trough through a reverse nozzle 57 to drive the rotor in the opposite direction. If desired, this valve 65 may be turned until its port registers with

passage 52 so that through it additional fluid may be introduced into the rotor through the passage 52.

What I claim is:

1. In a turbine, a rotor having two annular concentric trough-like structures of unlike diameters situated one within the other and open toward each other, and a nozzle block between and covering portions of the open sides thereof. 75

2. In a turbine, a rotor having two annular trough-like structures open toward each other, rotor rings therein dividing each rotor-trough into a plurality of parallel channels, and a nozzle block between and covering portions of the open sides thereof and arranged to introduce motive fluid into one of the rotor troughs. 80

3. In a turbine, a rotor having two annular trough-like structures open toward each other, a stationary nozzle block and a movable block between said troughs and covering portions of the open sides thereof. 85

4. In a turbine, a rotor having two annular concentric trough-like structures of unlike diameters situated one within the other and open toward each other, and a plurality of nozzle blocks spaced about the rotor between said troughs and covering portions of the open sides thereof. 90

5. In a turbine, a rotor having two annular trough-like structures open toward each other, a plurality of stationary nozzle blocks and a movable block adjacent each nozzle block, all of said blocks being spaced about the rotor between said troughs and covering portions of the open sides thereof. 95

6. In a turbine, a rotor having two annular trough-like structures open toward each other, a stationary block having therein a nozzle adapted to introduce motive fluid into one of the rotor-troughs, and another block forming with said stationary block a passage for leading motive fluid from one of said rotor troughs to the other, both of said blocks being between and covering portions of the open sides of the rotor troughs. 105

7. In a turbine, a rotor having two annular trough-like structures open toward each other, a stationary block having therein a nozzle adapted to introduce motive fluid into one of the rotor troughs, and another block forming with said stationary block a passage for leading motive fluid from one of said rotor troughs to the other, both of said blocks being between and covering portions of the open sides of the rotor troughs; and means for shifting the relative positions of said blocks to vary the size of said passage. 110

8. In a turbine, a rotor having two annular trough-like structures open toward each other, rotor rings therein dividing each rotor trough into a plurality of parallel channels, a stationary block having therein a nozzle adapted to introduce motive fluid into 115

one of the rotor troughs and a movable block forming with said stationary block a passage for leading motive fluid from one of said rotor troughs to the other, both of said blocks being between and covering portions of the open sides of the rotor troughs; and manual means for shifting the position of said movable block toward or away from the stationary block to thereby vary the size of said passage.

9. In a turbine, a rotor having near the periphery thereof two annular trough-like structures open toward each other, rotor rings therein dividing each rotor trough into a plurality of parallel channels, a plurality of stationary nozzle blocks and a movable block at one end of each nozzle block, all of said blocks being spaced about the rotor between said troughs and covering portions of the open sides thereof, each nozzle block being provided with means for introducing motive fluid into one of the rotor troughs and constructed to form with its adjacent movable block a passage for leading fluid from one of the rotor troughs to the other.

10. In a turbine, a rotor having near the periphery thereof two annular trough-like structures open toward each other, corrugated rotor rings therein dividing each rotor trough into a plurality of parallel wavy channels, a plurality of stationary nozzle blocks and a movable block at one end of each nozzle block, all of said blocks being spaced about the rotor between said troughs

and covering portions of the open sides 35 thereof, each nozzle block being provided with means for introducing motive fluid into one of the rotor troughs and constructed to form with its adjacent movable block a passage variable in size for leading fluid 40 from one of the rotor troughs to the other.

11. In a turbine, a rotor having near the periphery thereof two annular trough-like structures open toward each other, corrugated rotor rings therein dividing each rotor 45 trough into a plurality of parallel wavy channels, a plurality of stationary nozzle blocks and a movable block at one end of each nozzle block, all of said blocks being spaced about the rotor between said troughs 50 and covering portions of the open sides thereof, each nozzle block being provided with an expansion nozzle for introducing motive fluid into the outer rotor trough from the inside, and constructed to form 55 with its adjacent movable block a passage variable in size for leading fluid from said outer rotor trough to the inner rotor trough, and manual means for simultaneously shifting the positions of all of the movable 60 blocks.

In testimony whereof, I have hereunto set my hand this 1st day of August, 1912, in the presence of two witnesses.

EMIL ANDERSON.
